FIG. 1 is a right rear perspective view of a bicycle basket in accordance with our new design.

FIG. 2 is a left front perspective view of the design of FIG. 1.

FIG. 3 is a top plan view of the design of FIG. 1.

FIG. 4 is a front elevational view of the design of FIG. 1.

FIG. 5 is a rear elevational view of the design of FIG. 1.

FIG. 6 is a left side elevational view of the design of FIG. 1; and,

FIG. 7 is a right side elevational view of the design of FIG. 1. The broken line showing a bicycle is for the purpose of illustrating environmental structure and forms no part of the claimed design.
